DESIGN FOR A COMBINED CHEESE HOLDER AND GRATER

Robert Anstead, Beverly Hills, Calif.

Application November 12, 1940, Serial No. 96,498

Term of patent 7 years

To all whom it may concern:

Be it known that I, Robert Anstead, a citizen of the United States of America, residing in Beverly Hills, county of Los Angeles and State of California, have invented a new, original, and ornamental Design for a Combined Cheese Holder and Grater, of which the following is a specification, reference being had to the accompanying drawings, forming part thereof, wherein

Figure 1 is an elevational view of a combined cheese holder and grater, showing my new design; and

Figure 2 is an elevational view thereof, in an extended position.

Figure 3 is an elevational view of the grater member of the article; and

Figure 4 is an elevational view of the holder member of the article.

Figure 5 is a bottom plan view of the grater member shown in Figure 3; and

Figure 6 is a bottom plan view of the holder member shown in Figure 4.

I claim:

The ornamental design for a combined cheese holder and grater, substantially as shown.
